Primary Examiner — Kathleen L Jones

(57) **CLAIM**

The ornamental design for a mobile phone holder, as shown and described.

DESCRIPTION

FIG. 1 is a front and top perspective view of a mobile phone holder, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged perspective view of detail "9" identified in FIG. 2; and,

FIG. 10 is another perspective view thereof, shown in an alternative position.

The dashed lines in the figures illustrate portions of the mobile phone holder that form no part of the claimed design. The dash dot dash lines in FIGS. 2 and 9 are for the purpose of illustrating the enlarged views indicators and form no part of the claimed design.

1 Claim, 10 Drawing Sheets
